Edward Davis

UNITED STATES PATENT OFFICE.

CARL ALtenBURGER, OF MORRISTOWN, NEW JERSEY.

PREHEATING PISTON FOR INTERNAL-COMBUSTION ENGINES.

Application filed June 17, 1921. Serial No. 478,224.

To all whom it may concern:

Be it known that I, CARL ALtenBURGER, a citizen of the United States of America, and a resident of the town of Morristown, in the 5 county of Morris and State of New Jersey, have invented certain new and useful Improvements in Preheating Pistons for Internal-Combustion Engines; and I do hereby declare the following specification to be a 10 full, clear, and exact description of my said invention, such as will enable others skilled in the art to which it appertains to make and use the same, reference being had to the accompanying drawings, and to the characters 15 of reference marked thereon, which form a part of this specification.

My invention relates broadly to pistons for internal-combustion engines, in which a charge of gasified fuel is introduced into a 20 cylinder, compressed by a piston and then ignited into explosive combustion. More particularly considered, my invention relates to the piston-crown in such an engine and to means associated therewith adapted to pre- 25 heat the charges of said gaseous fuel prior to compression and explosion.

My invention has for its objects the provision of means, associated with the crown of the piston, in an internal combustion or 30 explosion engine, adapted to absorb a part of the heat developed by the explosion of a charge of gaseous fuel and to radiate such heat so absorbed, and thereby to raise the temperature of succeeding charges of said 35 fuel prior to their combustion and as introduced into the compression chamber of the cylinder in which said piston works. Further objects are the saving of fuel by a more efficient conversion thereof into expanded 40 gases; the increased capacity for the use of lower grade hydrocarbons and the capability of use of low grade fuels with beneficial results; and the production of increased power by acceleration of the combustion, ex- 45 plosion and expansion of the charge and by the more complete combustion of the fuel upon such explosion thereof.

With the foregoing objects and others to be hereinafter more particularly pointed out, 50 my invention consists in increasing the heat-absorbing and radiating capacity of that part of the wall of the piston in contact with the fuel. The preferred physical embodiment of my invention shown and described 55 consists in associating with the crown or upper and outer face of the piston a thickness

of metal affording air or gas circulation passages around and about it, also through it and between it and the piston-crown, whereby a maximum surface is attained for contact with the heated gases resultant from an initial explosive stroke and for contact with 60 succeeding charges of gas to be heated by radiation and convection therefrom.

In the accompanying drawings forming a 65 part of this specification and in which like numerals indicate the same or corresponding parts throughout the several views, Figure 1 is a perspective view in elevation of a piston-head to which my gas pre-heating 70 means is shown applied, part of the head and preheating means being broken away and the underlying configuration of the piston-head being indicated by dotted lines. Figure 2 is a plan-view on the line 2—2 of 75 Figure 1, viewed in the direction indicated by the arrow, a part of the gas-preheating means being broken away to show the webs and channels between it and the piston-face. Figure 3 is a plan-view, similar to Figure 2, 80 of a modification of the gas-preheater, consisting of an alternative arrangement of the webs connecting a circular preheater plate to the piston face and of the channels for circulating the gas thereabout. Figure 4 is 85 a sectional elevation on the line 4—4 of Figure 3, showing the preheater and a fragment of the piston-head.

Throughout these views, the numeral 1 indicates a piston-head, hollow and having the 90 usual packing rings and trunnion bearings as indicated in dotted lines; 2 is the outer, bevelled edge thereof. In Figures 1 and 2, 3 is an annular plate, having the central aperture 4, and attached to said crown by 95 the webs 5 having air- or gas-passages 6 therebetween.

The preferred form of preheating means illustrated is in the form of an annulus of washer form, mounted upon the piston-crown, spaced apart therefrom about one-eighth of an inch and itself of a thickness of about one-eighth of an inch, and having an outer diameter substantially three times that of the diameter of the circular central 100 aperture therethrough, said aperture being about one and one-quarter inches in diameter, and said outer diameter of the annulus being about three and one-quarter inches for a piston-face having a diameter over-all of 105 three and three-quarter inches. This annulus may be supported by webs connecting 110

it to the wall of the piston-head and cast integrally therewith, said webs being preferably concentrically disposed about the central circular aperture, and affording a plurality of radially disposed passage-ways therebetween to permit the circulation of gases thereabout and about the annulus and over the piston-crown. Obviously, the form of the means of mounting the annulus may 10 be varied and the mounting may be by other methods than by casting such means integrally, as by a similarly disposed interrupted flange depending from said annulus and welded to the piston-crown; or the pre- 15 heating plate may be fixed thereto in any suitable manner of securing same, as by rivets and spacing washers thereon. Such webs or connections are preferably of small cross-section in order to minimize the loss of heat 20 from the preheater plate by conduction to the piston-head.

In the modification illustrated, in Figures 3 and 4, the annulus is replaced by a central plate 7 having radial extensions 8 supported by webs 9 having channels 10 there- 25 between.

By the construction shown and described herein first-recited objects are attained and by virtue of the high temperature of the 30 preheater plate, the formation of carbon deposits thereon is prevented.

Having thus described my invention and the best means now known to me of practicing the same, but without desiring to be 35 understood as limiting the scope of the appended claims to the particular constructions shown and described, which, as will be well understood by those skilled in the art,

are susceptible of a wide range of variation and modification in many equivalent forms 40 without departing from the principle of their operation or the spirit of my invention, I claim:

1. In a piston for an internal combustion engine, means supported from the crown of 45 said piston adapted to increase the area of heat-radiating surface exposed directly to the explosive gas and comprising a metallic plate integral with said piston-crown and a chamber between said plate and said crown 50 in communication with the cylinder above the piston.

2. In a piston for an internal combustion engine, means adapted to increase the heat- 55 radiating surface of the piston-head exposed to the explosive gases and consisting of an annulus spaced from the crown of said piston-head and lying in a plane parallel thereto, and a plurality of webs connecting said annulus and said crown. 60

3. In a piston for an internal combustion engine, an annulus spaced from and mounted upon the piston-head in a plane parallel to the crown thereof, and a plurality of webs 65 concentrically disposed about the central aperture of said annulus and connecting it to said piston-head.

4. In a piston for an internal combustion engine, an annulus spaced from and mounted upon the crown of the piston in a plane parallel thereto, a plurality of webs connecting said annulus to said piston and adapted to afford a plurality of passages for the explosive gases between said annulus and said crown. 70

CARL ALTBURGER.
